**RAILWAY HOPPER CAR PIVOTED CLOSURE
LATCHING MECHANISM**
George B. Dorey, Westmount, Quebec, Canada, assignor
to Enterprise Railway Equipment Company, Chicago,
Ill., a corporation of Illinois
Filed Jan. 18, 1961, Ser. No. 83,521
5 Claims. (Cl. 105—248)

This invention relates to an improved vertically movable latching means for a hopper door construction for railway cars and the like and it has particular reference to a pivotally mounted door structure of the type generally used in connection with transversely mounted hopper doors.

In hopper cars of the identified type having the doors extending transversely of the car, a generally accepted method of latching the doors in closed position resides in the employment of independently functioning latching keepers located at the opposite sides of the car for retaining the opposite ends of the door structure in closed position. The system of independently latching and releasing the opposite ends of the doors in this manner generally requires that an operator be employed at each side of the car. This independent operation, furthermore, requires close cooperation between the operators at the opposite sides of the car to assure simultaneous release of the keepers at the opposite ends of the doors. Repeated failures in effecting the simultaneous release of the keepers at the opposite ends of the door structure eventually results in distortion of the doors, door bracing and supporting parts due to the weight of the lading being held at only one end of the door structure, as will be readily understood.

It is one of the objects of this invention, among others, to overcome the disadvantages incidental to independent latching and releasing of the keeper means at the opposite ends of the door structure by providing a latching mechanism which may be operated from either side of a car. Other objects are: To provide a bodily movable shaft member adapted to engage with shouldered keepers at the opposite ends of a door structure; to provide a latching shaft engaging with shouldered keepers located at the opposite ends of a door structure and at a location intermediate thereof; to provide a mechanism having keepers with stepped shoulders at a location intermediate the ends of a door structure for holding it in partly closed position and to provide other shouldered keepers adjacent the ends of the door structure having flared entrance ways to the shoulders for guiding the mechanism into latching position; and to provide a bodily movable latching shaft which may be readily applied or removed from a car door structure and mounted independently of a locking shaft.

The invention further resides in the novel methods employed for obtaining the desired results and in the details of construction incorporated in the improved structure. For further comprehension of the invention reference may be had to the accompanying drawings wherein the improvement is shown as applied to a hopper car having transversely mounted doors.

In said drawings:

FIG. 1 is a vertical transverse sectional view taken through the lower part of a railway hopper car and show-

2

ing a pair of doors in open position and with the improved latching mechanism applied thereto.

FIG. 2 is a side elevational view of the structure shown in FIG. 1 as viewed from left to right with the door shown by full lines in open pendant position and in conventional dot and dash lines as positioned when the latch deflector makes contact with the inclined runways of the side shouldered keepers on door closing movement.

10 FIG. 3 is a side elevational view, similar to FIG. 2, except that the door structure is shown in closed and latched position.

15 FIG. 4 is a vertical sectional view taken through the door structure showing the door in partially closed position as retained by the intermediate keepers, said view being taken at a location corresponding to a line 4—4 of FIG. 1.

20 FIG. 5 is still another vertical sectional view, similar to FIG. 4, taken through the door structure and showing the latching shaft in position as it is lifted by the outer keepers to engage the upper tips of the intermediate keepers preparatory to dropping into engagement with the secondary latching shoulders.

25 FIG. 6 is a horizontal sectional view taken through the doors and showing the auxiliary shaft with the eccentric end portions in blocking position, said view being taken on a line 6—6 of FIG. 1.

FIG. 7 is a fractional vertical sectional view taken through the door and on a line 7—7 of FIG. 1.

30 FIG. 8 is a diagrammatic view illustrating at an enlarged scale the contours of the forwardly projecting portions of the end and intermediate keepers.

FIG. 9 is a vertical sectional view of the lower portion of a car having a single door formed by a continuous door plate and the conventional center sill eliminated with a partition substituted therefor, said view showing the door in open position.

FIG. 10 is a side elevational sectional view of the structure shown in FIG. 9 as taken on a line 10—10 of FIG. 9.

40 FIG. 11 is a fractional sectional elevational view as an enlarged scale showing the linkage in extended position that is illustrated in folded position in FIG. 10.

Referring first to the structure shown in FIGS. 1-8 inclusive, 10—10 indicate the rails on which the car is mounted, 11 the center sill of the car and 12—12 the side wall angles or sills of the car. Interposed between the center sill 11 and side wall angles or sills 12—12 are hoppers A each having a discharge opening and a door B for closing the respective opening.

50 The hoppers A are disposed on opposite sides of the center sill 11 in transversely aligned relation. Inasmuch as the hoppers and doors are of similar construction, the description herein will be confined to only one hopper and door. Each hopper A is defined, in part, by upper and lower oppositely sloping floors 13 and 14 and inner and outer side walls as indicated at 15 and 16 respectively. The edge portions of said walls and floors are spaced from each other to form a discharge area which in turn is bordered by a frame 17.

55 Each frame 17 is preferably in the form of a lower stirrup portion including legs 18 and 19 which respectively overlie the side walls 15 and 16 and a lower portion 20 which underlies the lower sloping floor 14. The stirrup portion of the frame 17 is preferably T-shape in cross section with a stem 21 projecting

centrally outwardly from the overlying base portion 22 of the frame. The upper portion of the frame 17 includes a beam member 23 which underlies the upper sloping floor 13.

The upper beam member 23 is preferably of angle shape with one wall 24 underlying the floor 13 and the adjacent wall 25 projects downwardly and forwardly beyond the edge of the side walls 13 and 14 and with the outer portion of the base portion 22 forms a forwardly extending chute like structure. In the angle presented by walls 24 and 25 there are disposed pairs of hinge butts 26-26 which are apertured at 27 for receiving door pintles 28.

Pivotedly supported by the pintles 28 are the doors B each of which includes hinge straps 29-29 and a body plate portion 30 that is welded to the straps 29-29 as indicated at 31. Each door plate body portion is preferably of pan shape with an upturned marginal flange 32 and, when closed, assumes an inclined position to enclose the forwardly extending chute like structure of the frame 17.

The doors B-B can be connected by an angle bracing member 33 welded thereto, as indicated at 33', to form an assembly of the two doors and cause them to swing together as a unit. As will appear hereinafter, the angle bracing member 33 can be omitted and other means employed to effect conjoint operation of the doors B-B. The door assembly as composed of the two doors B-B hangs in a substantially vertical open position, as shown in FIGS. 1 and 2, and is adapted to be kicked or swung toward its closed position to meet with the sloping floor 14 and be there retained by latching mechanism which will now be described.

The latching mechanism includes outwardly spaced shouldered keepers 34-34 and intermediately located shouldered keepers 35-35. The outer keepers 34-34 are disposed outwardly beyond the ends of the door assembly and are carried by the hopper outer side walls 16-16. The keepers 35-35 are carried by the hopper inner side walls 15-15. Cooperating with the shouldered keepers 35-35 is a latching shaft section 36 which is bodily movable and arranged to be moved by rotation. The shaft section 36 is provided with radially extending arms 37-37 which pivotally connect at 38-38 with one end of links 39-39 which in turn connect at 40-40 with lugs 41-41. The lugs 41-41 are carried by bracket bars 42 which preferably consist of flat bars welded or otherwise secured to the outer face of the doors B-B as indicated at 43.

The pivots 38-38 and 40-40 extend slightly beyond the associated links 39-39 and may be welded thereto. The axes of said pivots 38 and 40 are preferably so related to each other and to the axis of each latch shaft section 36 that a straight line 45 (FIG. 7) extending through said axes of the said pivots will pass substantially through and slightly to one side or slightly beyond and to one side of the axis 46 of the latch shaft section 36, when in closed position, in order to provide a closed toggle mechanism. The links 39-39 are indented at 47 to allow for the seating of the shaft section 36 in closed toggle position.

The latch shaft section 36 is confined in its bodily movement to a given path between inner and outer guiding walls 48 and 49, FIG. 7, the latter consisting of flat plates bent inwardly to present upper and lower walls indicated at 50 and 51 respectively. The upper walls 50 are welded to the inner walls 48 at 52 and the lower walls 51 are welded to the bracket bar 42 at 54. The adjacent ends of the shaft sections 36 are connected by a sleeve member 55 which extends for a short distance over each shaft section and is welded thereto at 56. The two shaft sections 36, when united by the connecting sleeve 55, function in unison as a single latch shaft.

Cooperating with the latch shaft structure to retain the door assembly in closed position are the shouldered

keepers 34-34 and 35-35, respectively, disposed adjacent the opposite ends of the door assembly and intermediately thereof. The said keepers 34-34 and 35-35 include shouldered portions 57 which are disposed in alignment with each other, FIG. 8, to engage with the shaft sections 36 of the shaft assembly for retaining the doors B-B in fully closed position.

The intermediate keepers 35-35 function to hold the door assembly in partially closed position and the outer keepers 34-34 operate to ease the portions of the shaft assembly which overhang the intermediate keepers 35-35 into engagement with the final locking shoulders 57. To this end the intermediate keepers 35-35 are each provided with a secondary shoulder 60, FIG. 8, stepped from the main shoulder 57 and connected therewith by an inclined surface 61. Each outer keeper 34 includes a flared approach to the main shoulder 57 formed by an inclined surface 62 corresponding to the inclination of the inclined surface 61. The inclined surface 62 is projected well beyond the secondary shoulder 60 and thus presents a wide angle approach to the locking shoulder 57.

The outer end of each shaft section 36 of the assembly is formed with a deflector 63 having a lower arcuate surface 64 adapted to ride on inclined runways 65-65 of the related outer keepers 34-34. Each runway 65 leads to its inclined surface 62 and the junction 66 of the runway 65 with surface 62 is disposed substantially in horizontal alignment with the upper tip 67 of the secondary shoulder 60. The surface of each runway 65 lies slightly above the nose 68 of the respective intermediate keeper 35 thus compelling displacement of the shaft assembly solely by contact with the outer keepers 34-34.

Extending laterally outwardly from each deflector 63 is a projection 69 which, in cooperation with a fulcrum 70 extending laterally from the related outer keepers 34, allows the insertion of a prying bar 71, FIG. 3, therebetween for levering the latch shaft assembly in either latching or unlatching movements.

To prevent accidental release of the latch mechanism an auxiliary shaft 72 extends from side to side of the doors B-B and at the ends thereof is provided with eccentric portions 73-73 for engagement with lugs 74-74 on the shaft sections 36-36. The said eccentric portions 73 are preferably in the form of circularly shaped bars bent to present angularly related portions 75-75 and 76-76 with the former welded at 77 to the shaft 72 and the companion arm extending at an acute angle to form an operating handle. The shaft 72 is journaled in bearings 78 which are preferably of U-shape and disposed outwardly of the outer guiding wall 49.

As shown in FIG. 7, the U-shaped bearings 78 are preferably formed of a plate bent to a U-shape with one of the walls 79 longer than the opposite wall 80. The bearings 78 are applied in position with the longer wall 79 resting on the inwardly extending upper wall 50 of the outer guiding wall 49 and said walls 79 and 80 are welded at 81 and 82 to the overlying wall member. An abutment 83 is welded at 84 and 85 to the lower wall 80 of each bearing 78 to limit swinging movement of the shaft 72 in either direction.

As pointed out hereinbefore, the angle bracing member 33 can be omitted if the latching shaft sections 36-36, joined by the sleeve member 55, and the auxiliary shaft 72 are of sufficient size to provide the necessary mechanical interconnection between the doors B-B.

Referring now to the modification shown in FIGS. 9 to 11 inclusive, it will be noted that the improvement is shown as applied to a car without a center sill and wherein the door plate extends continuously from side to side of the car. In FIGS. 9 to 11 the side wall angles or sills of the car are indicated at 90-90 and the hopper structure is formed in part by upper and lower sloping floors 91 and 92 respectively which meet with inwardly slop-

ing side walls 93—93. Adjacent the side walls 93—93 there are triangular shaped floor sections 94—94, the edge portions of which cooperate with the edge portions of the sloping floors 91 and 92 to define a rectangularly shaped discharge area.

The discharge area is bordered by a framework including upper, lower and side sections shown at 95, 96 and 97—97, respectively. The said frame members are preferably of angle shape with one of the flanges 98 underlying the upper floor sheet 91 and the adjacent flange 99 projecting forwardly to form a four sided chutelike extension 100. The upper part of the frame is provided with apertured hinge butts 101 for receiving door pintles 102 to pivotally support hinge straps 103 which are secured to a door 104.

The door 104 is preferably formed of metallic plate having the margins flared upwardly as at 105 to form a pan shape enclosure which embraces the forwardly projecting chute 100 of the frame, when the door 104 is in closed position. Midway of the discharge area there is disposed a hollow hood like portion 106 preferably formed of two plates 107—107 which are welded at 108 to the flange 99 of chute 100 and to the lower sloping floor 92 at 109.

Latching means for retaining the door 104 in closed position include outer shouldered keepers 110—110 carried by the hopper side walls 93—93 and an intermediate located shouldered keeper 111. The shoulders 112 of the outer keepers 110—110 and of the intermediate keeper 111 are disposed in aligned relation.

Cooperating with the shouldered keepers 110—110 and 111 is a bodily movable shaft 113 having a series of axially spaced radially extending arms 114 welded thereto. The arms 114 are pivotally connected at 115 to one end of links 116 which in turn are pivotally connected at their opposite ends at 117 to straps 118. The link and shaft assembly, which is shown in extended position in FIG. 11, is folded to bring the shaft 113 in bearing relation with the outer face 119 of the straps 118.

The straps 118 are retained against the outer face of the door 104 by welding, as indicated at 120, and constitute the inner walls of guiding slots for confining the movement of the shaft 113 to a given path. The outer wall of the slots is formed by downward extensions 121 of the hinge straps 103 which are brought outwardly at 122 to overlie the shaft 113 throughout its range of movement.

The ends of the shaft 113 are formed with arcuate shaped deflectors 123, similar to the deflectors 63 previously described, which engage with inclined runways 124—124 on the outer keepers 110—110 for displacing the shaft 113 upwardly as the door 104 is swung toward closed position. The upward movement of the shaft 113 is carried out solely by the outer keepers 110—110 inasmuch as the inclined runways 124—124 are disposed beyond the outer surface 125 of the nose of the intermediate keeper 111.

The intermediate keeper 111 is provided with an auxiliary shoulder 126 stepped from the main shoulder 112 for maintaining the door 104 in partially closed position. The auxiliary shoulder 126 is connected with the main shoulder 112 by an inclined surface 127. The approach to the main shoulder 112 of each outer keeper 110 is an inclined surface 128 extending substantially in parallelism with the inclined surface 127 of the intermediate keeper 111 and is projected well beyond the auxiliary shoulder 126 to contact the overhanging portions of the shaft 113 when it is held by the auxiliary shoulder 126.

The ends of the shaft 113 are provided with crank like portions 129 which in cooperation with fulcrums 130—130 on the outer keepers 110—110, provide rests for a prying bar (not shown) in opening or closing the door 104.

The latching shaft 113 is retained in position and maintained against accidental release by an auxiliary shaft 131 which is journaled in bearings 132 formed in

tegally with the hinge straps 103. The auxiliary shaft 131 is provided at each end with an eccentrically disposed portion 133 which is adapted to lie in the path of swinging movement of the adjacent link 116 when the auxiliary shaft 131 is rotated inwardly toward the door 104 from the position shown in FIG. 10. Each end of the auxiliary shaft 131 is provided with a handle portion 134 which makes contact with an abutment 135 on the respective hinge strap 103 for limiting its movement in either direction.

The intermediate keeper 111 is sandwiched between the partition plates 107—107 and riveted thereto as indicated at 136. The door 104 is apertured at 137 for the passage of the intermediate keeper 111 therethrough. It is apertured also at 138 for the passage of a brake rod 139 therethrough, said rod being also passed within the housing 106.

If desired, an angle reinforcing member 140 can be suitably secured, as by welding, to the lower front portion 20 of the door 104 to rigidify it and prevent warping.

What is claimed as new is:

1. In a railway hopper car having a discharge opening and a door structure pivotally mounted adjacent the upper part of the opening and swingable to an open pendant position, in combination:

(a) latching means for retaining the door structure in closed position including:

- (1) a bodily movable shaft, and
- (2) shouldered keeper means,

(b) said shouldered keeper means including end keeper means and intermediate keeper means,

(c) means movably mounting said shaft on said door structure with the ends of said shaft projecting beyond the ends of said door structure,

(d) said keeper means being mounted on the hopper car with said end keeper means engaging the projecting ends of said shaft and cooperating therewith to guide said projecting ends of said shaft along predetermined paths during the final closing movement of said door structure and said intermediate keeper means engaging said shaft at a location intermediate its ends when said door structure is swung to closed position, and

(e) said intermediate keeper means having stepped shoulders for retaining the door structure in partially closed position while said end keeper means hold steady said projecting ends of said shaft.

2. The invention, as set forth in claim 1, wherein:

(a) the intermediate keeper means is located centrally of the door structure, and

(b) the end keeper means have flared approaches to their supporting shoulders for easing the ends of the shaft into retaining position with their shoulders compensating for teetering movement of the door structure about said intermediate keeper means.

3. The invention, as set forth in claim 2, wherein:

(a) shoulder portions on the end keeper means are in alignment with a shoulder portion on the intermediate keeper means,

(b) the shaft is bodily movable by rotation, and

(c) the flared approaches on the end keeper means lead from the supporting shoulders thereon at a non-retaining angle for guiding the ends of said shaft and moving it by rotation into engagement with said supporting shoulders.

4. The invention, as set forth in claim 3, wherein the stepped shoulders on the intermediate keeper means are connected by an inclined surface corresponding substantially to inclined runways on the end keeper means presented by the flared approaches thereof and in substantial alignment therewith.

5. The invention, as set forth in claim 1, wherein:

(a) the door structure comprises a pair of doors each individual to a hopper having inner and outer side walls with the inner walls disposed adjacent a center

- sill of the car and a sloping floor terminating at the bottom of the hopper opening closed by the respective door,
- (b) the doors are hinged to the hoppers adjacent an upper side thereof and are swingable by gravity to the open position,
- (c) the end keeper means are mounted on the outer side walls of the respective hoppers and the intermediate keeper means are mounted on the inner side walls of the respective hoppers.
- (d) the shaft is movable by rotation and extends parallel to the hinge axis of said doors and adjacent the edges thereof furthest removed from said hinge axis and projects beyond said doors at its ends to engage with the shoulders of said end keeper means to hold said doors closed, and

5

10

15

- (e) said end keeper means have flared approaches to their retaining shoulders to guide the ends of said shaft into engaging relation with said retaining shoulders.
